MILL TABLE FEED DEVICE

Francis L. Moseley, 700 Flintridge Drive, Pasadena, Calif.

Filed Aug. 13, 1965, Ser. No. 86,580

Term of patent 14 years

(Cl. D55—1)

FIG. 1 is a view of the right side of a mill table feed device in accordance with my new design;

FIG. 2 is a rear elevation thereof;

FIG. 3 is a front elevation thereof; and

FIG. 4 is a view of the left side thereof.

The dominant features of my design reside in the portions shown in full lines only.

I claim:

The ornamental design for a mill table feed device, as shown and described.
